ALUMINUM RECORD BLANK

Junius D. Edwards, Oakmont, Pa., assignor to
Aluminum Company of America, Pittsburgh,
Pa., a corporation of Pennsylvania

Application July 25, 1936, Serial No. 92,596

3 Claims. (Cl. 274—42)

It has been the practice to make sound recordings on aluminum discs by means of a diamond or sapphire stylus or its equivalent. The stylus is caused, by electrical means, to vibrate laterally with a frequency corresponding to the sound being recorded, while the aluminum disc is caused to revolve at a constant speed beneath the stylus. The stylus is moved across the face of the disc at a uniform speed, so that it impresses a uniformly spaced spiral groove in the surface of the disc. The aluminum records so produced have advantages over other types of sound records; for example, they may be used directly for sound reproduction without the necessity of preparing master records in other materials.

For many uses the fidelity and tonal quality of reproduced sound is satisfactorily supplied by current methods of recording. The outstanding problem, however, has been to reduce excessive noise introduced by irregularities in the sound track other than those representing the recorded sound. These irregularities and the resultant noise in reproduction appear to be caused by a tearing action of the stylus during recording. The proper function of the recording stylus is to press or "rub" the sound groove into the metal without tearing or cutting the surface. It is possible, by proper shaping of the stylus and adjustment of the recording conditions, to produce a sound record on bare aluminum which is satisfactory for many requirements. It is also possible, where the adjustment of the stylus does not represent optimum recording conditions, to reduce the background noise somewhat by lubricating the disc with mineral oil or paraffin, and this has been a common practice in the past. The demands of the art, however, have become so exacting that even these expedients have not been adequate where the highest tonal quality and freedom from noise are demanded.

It is an object of the present invention to provide a method of recording on aluminum for direct sound reproduction which will substantially reduce the background noise experienced with aluminum records as made by the best technique heretofore employed. More particularly, it is an object of the invention to provide a means of treating the surface of the discs so that the stylus will rub the sound groove into the record without tearing or cutting the surface. A further object is to provide a method of treating the surface of the sound recording blank so that sound may be reproduced with optimum fidelity and tonal quality. Other and further objects will appear as the description proceeds.

According to the invention, the aluminum

blank, before recording, is provided with an adsorbed coating of a fatty acid possessing lubricating qualities, such as ricinoleic acid. The material used apparently—although I do not wish to be bound by any theory—is strongly adsorbed by the aluminum surface and held thereon. Even at the extremely high pressure at the point of the stylus, which high pressure is necessary to permit rubbing the groove into the solid aluminum, the material remains adherent to the aluminum and permits the recording stylus to produce flow in the metal without tearing or cutting. Under some conditions, when ricinoleic acid is used, it may fail, some time after application, to wet the surface, and this difficulty can be overcome by mixing the ricinoleic acid with mineral oil in amount sufficient to give a completely miscible mixture.

This treatment effects a reduction of noise level, in some cases, of as much as three or four decibels as determined by comparison with the best prior practices in recording and reproduction.

Referring to the drawing, Fig. 1 is a plan view, and Fig. 2 is a sectional view, of a sound recording blank treated in accordance with my invention. It will be understood that, for the purposes of illustration, the thickness of the coating is exaggerated in Fig. 2. Figure 3 is a fragmentary sectional view of a sound recording blank treated in accordance with my invention, and with a sound groove or track impressed therein, the coating also being shown as exaggerated in this figure.

The treated blank with the sound groove impressed therein may be played without further treatment, or it may be cleaned by any suitable method and provided with an artificially produced oxide coating carrying an adsorbed lubricant to improve its reproducing characteristics as disclosed in my United States Letters Patent No. 2,085,741, dated July 6, 1937, to provide an article such as that claimed in that patent.

It will be understood that modification of the invention will be limited only as defined in the appended claims.

I claim:

1. A sound recording blank comprising an aluminum disc coated with a fatty acid having lubricating properties.

2. A sound recording blank comprising an aluminum disc having ricinoleic acid thereon.

3. A sound recording blank comprising an aluminum disc having on its surface a fatty acid having lubricating properties and characterized by the property of remaining in situ under the pressure exerted by a recording stylus.

JUNIUS D. EDWARDS.
